(57) **CLAIM**

The ornamental design for a shoe sole, as shown and described.

DESCRIPTION

FIG. 1 is a left-side view of a shoe sole in accordance with our new design;

FIG. 2 is a right-side view thereof;

FIG. 3 is a front view thereof;

FIG. 4 is a rear view thereof;

FIG. 5 is a top view thereof;

FIG. 6 is a bottom view thereof;

FIG. 7 is an enlarged view of the portion of the shoe sole shown within the area designated as 7 in FIG. 3;

FIG. 8 is an end view taken along line 8-8 of FIG. 6; and, FIG. 9 is an enlarged view of the portion of the shoe sole shown within the area designated as 9 in FIG. 8.

The broken lines shown in the figures depict portions of the shoe sole that form no part of the claimed design. The dash-dot-dash lines shown in the figures represent the bounds of the claimed design.

1 Claim, 7 Drawing Sheets
